UNITED STATES PATENT OFFICE.

ARTHUR R. HAVENER, OF WAYLAND, MASSACHUSETTS, ASSIGNOR TO AMERICAN
LACING HOOK CO., A CORPORATION OF NEW JERSEY.

STOP MECHANISM.

Original application filed November 23, 1918, Serial No. 263,833. Divided and this application filed May 5, 1921. Serial No. 466,959.

To all whom it may concern:

Be it known that I, ARTHUR R. HAVENER, a citizen of the United States, residing at Wayland, in the county of Middlesex and 5 State of Massachusetts, have invented new and useful Improvements in Stop Mechanism, of which the following is a specification.

This invention relates to an improved 10 stop mechanism, the object of the invention being to provide a mechanism which will automatically stop a machine at the end of a predetermined number of rotations of the driving shaft of the machine, or at the end 15 of a predetermined number of sequences of operations of said machine.

The invention is particularly adapted to 20 be used in connection with lacing hook setting machines for boots and shoes and has been shown and described in my application filed November 23, 1918, Serial No. 263,833 patented May 24, 1921, No. 1,379,303 for lacing stud setting machine with automatic stop, the subject-matter of this case 25 being divided out of said application.

The invention consists in the combination and arrangement of parts set forth in the following specification and particularly pointed out in the claims thereof.

30 Referring to the drawings:

Figure 1 is a right hand side elevation of a machine embodying my invention.

Fig. 2 is a detail plan partly in section taken on line 2-2 of Figure 1, illustrating the mechanism connecting with the clutch to automatically stop the machine.

Fig. 3 is a detail section taken on line 3-3 of Figure 1.

40 Fig. 4 is a detail section partly in elevation taken on the line 4-4 of Figure 2.

Figs. 5 and 6 are detail sectional plan views taken on line 6-6 of Fig. 4.

45 Fig. 7 is a side elevation partly broken away and shown in section illustrating a portion of the mechanism which operates the clutch to automatically stop the machine.

Fig. 8 is a transverse section taken on the 50 line 8-8 of Fig. 7 looking toward the right in said figure and presenting a rear elevation of the parts illustrated in Fig. 7.

Fig. 9 is a sectional elevation taken on line 55 8-8 of Fig. 7 looking toward the left in said figure.

Fig. 10 is a detail plan view partly in sec-

tion of a portion of the mechanism for operating the clutch mechanism.

Like numerals refer to like parts throughout the several views of the drawings.

In the drawings, 20 is the frame of the 60 machine and 21 the main driving cam shaft which is driven by means of a clutch 19, said clutch comprising a clutch pulley 22, constituting a driving member, which rotates loosely upon the driving shaft 21 until locked by a locking dog 24 to a clutch member 23 which is fast to said shaft 21 and constitutes a driven member. The clutch 19 is operated to start the machine 65 by a rod 25 connected to a suitable treadle (not shown in the drawings), said treadle being moved to lower the rod 25 and thereby rock a lever 26 pivoted at 27 to the frame of the machine and, through an arm 28 and pin 29, operates a spring actuated tripper 70 slide 30 which, when withdrawn from in front of the locking dog 24, will allow said locking dog to engage the driving pulley 22, whereupon said driving member 22 and said driven member 23 will be locked together 75 80 in a manner well known to those skilled in this art. It will be seen that the pin 29 forms, in effect, a portion of the tripper slide 30. The novel features of this invention whereby the driving member 22 and driven member 23 are automatically disengaged to stop the machine will be hereinafter fully described.

The member 35 constitutes a portion of a 90 work support 32 and is screwed to the frame 20. A presser foot 38 is adapted to be raised by foot power from the treadle, or automatically, by power from the main driving shaft. When the rod 25 is pushed upwardly it rocks an arm 39, Fig. 8, which is fastened to a rock-shaft 40. The rock-shaft 40 is journalled to rock in bearings 41 on the right hand side of the frame (see Figure 1).

100 Adjustably fastened to the front end of the rock-shaft 40 is an arm 42, the free end of which bears against the bottom of a rod 43 adapted to slide vertically in bearings 44 on the right hand side of the frame 20. The presser foot 38 is adjustably fastened 105 to the rod 43 by a screw 45. A spring 46 presses the rod 43 downwardly.

110 A rock shaft 61 is journalled to rock in bearings 62 in the frame 20. A rocking motion is imparted to the shaft 61 by means

of a link 67 pivotally connected at its upper end to an arm 68 fast to the shaft 61, and pivotally connected at its lower end to a cam lever 69 which is rocked upwardly and downwardly by cams 70 and 71 which are fast to the main shaft 21.

A lever 119 is pivoted upon a vertical stud 120 which is mounted in the presser foot 38 and is rocked upon said stud 120 by motion transmitted by a rod 121 connected to a bell crank lever 122 pivoted at 123 to a bracket 124 fast to the frame 20. The connecting rod 121 is constructed in two sections 125 and 126 which are adapted to 10 be adjusted relatively to each other to increase or diminish the length of the rod by means of a turn buckle 127 and cooperating lock nuts 128. The rod 121 is connected at one end to the lever 119 by means of a clamping member 129 having a recess 130 adapted to fit the spherical head 131 of a pin 132 fast to the lever 119, and the other end of said rod is similarly fastened to the bell crank lever 122 by the clamping member 133 having a recess 134 which fits the spherical head 135 of a pin 136 which is fastened in an arm 137 of said bell crank lever 122.

It will thus be seen that the rod 121 makes a universal connection between the levers 119 and 122 to allow for the horizontal movement of said levers and for the vertical movement of the presser foot 38. The other arm 138 of the lever 122 has journaled thereon a cam roll 139 which engages a cam 140 fast to the link 67. The upper portion of the cam 140 is cylindrical, while the lower portion 141 is substantially conical, see Fig. 7.

A spring 142 keeps the roll 139 in engagement with either the cam 140 or the link 67. Thus it will be seen that with each downward movement of the link 67 the cam 140 will descend and the cam roll 139, which has been engaging said link 67, as illustrated in Fig. 2, will engage the substantially conical portion 141 of the cam 140 and cause the lever 122 to rock in the direction of the arrow *a*, Fig. 2, and thus through the mechanism just described cause the lever 119 to rock on its pivot 120.

Referring to Figs. 2, 4, 5, 6 and 10, it will be seen that the lever 119 is adapted to be rocked upon the stud 120, as previously described, and has formed integral therewith an arm 161. This arm 161 has fast therein the pin 132 previously referred to, said pin having a portion 162 extending downwardly into a pawl 164 which has projecting therefrom a pin 165 which is engaged by a lever 163 pivoted upon the portion 162 of the pin 132.

A spring 166 connected to the lever 163 always tends to keep said lever in engagement with the pin 165. The pawl 164 has a cylindrical stem 167 projecting from its lower side which has a reduced portion 168

formed therein which is adapted to fit and slide in a slot 169 formed in a plate 170 mounted on a block 171 upon the plate 35 forming a part of the work support 32. The slot 169 is formed concentric with the center of the stud 120 and the pawl 164 is moved forward and backward upon the plate 170 by the rocking movement of the lever 119. The pawl 164 is prevented from moving vertically upon the plate 170 by shoulders 172 and 173 formed by the reduced portion 168 of the stem 167.

When the presser foot 38, together with the mechanism mounted thereon, is raised the pawl 164 will remain stationary, the portion 162 of the pin 132 sliding vertically therein as illustrated in Fig. 4. The pawl 164 engages the teeth 174 of a ratchet 175, and the spring 166, pulling upon the lever 163 which, in turn, is engaging the pin 165, normally tends to keep the pawl 164 in engagement with the teeth 174. The ratchet 175 is fast to the stud 120 and has a series of holes 1, 2, 3, and 4 therein arranged concentric with the center of said stud.

A setting pin 177 may be placed in any one of said holes and a coil spring 178 fast at one end to the frame 20 and at the other end to a pin inserted in the periphery of the ratchet 175 normally tends to pull the setting pin 177 toward and against a stop formed by the side of the presser foot 38.

Loosely mounted upon the stud 120 is a latch 193 normally held in the position illustrated in Fig. 2 by a coil spring 194 which is fast at one end to the frame 20 and at the other end to an arm 195 formed on said latch. The latch 193 also has an arm 196 with a notch 197 in its outer end. A pin 198, projecting upwardly from the ratchet 175, is adapted to engage the arm 196 at certain times in the operation of the mechanism and rotate said latch upon the stud 120.

A locking pawl 199 is pivoted at 200 upon the block 171 and is adapted to engage the teeth 174 of the ratchet 175. A flat spring 201 normally holds the pawl 199 against a stop pin 202 and in engagement with the teeth 174 to hold the ratchet 175 against rotation thereof by the spring 178, while the pawl 164 is moving backward to engage another tooth.

Before starting the machine the operator inserts the pin 177 in one of the holes 1, 2, 3 or 4 in the ratchet 175, for example, if he desires to have the cam shaft rotate six times before it automatically stops, he places the pin 177 in the hole 1. If he desires to have said shaft rotate five times before stopping he places the pin in the hole 2. If he desires to have the shaft rotate four times, he places the pin in the hole 3 and if he desires to have the shaft rotate three times, he places the pin in the hole 4.

In the drawings, see Fig. 2, the pin is placed in the hole 1 and is held against the side of the presser foot 38 by the spring 178.

Referring now to Figs. 1, 2, 5, and 6, it will be seen that a rod 205 is mounted upon the frame 20 and is slideable horizontally in bearings 206 and 207. The rod at its front end is bent downwardly at 208 in order that it may be engaged by the arm 195 of the latch 193 at the proper time, and thereby be moved from the position illustrated in Fig. 5 to that illustrated in Fig. 6. The other end of the rod 205 is connected by a pin 209 to an arm 210 fast to a rock-shaft 211 mounted in bearings 212 at the rear of the machine.

A second arm 213 is fastened to the rock-shaft 211 and has pivoted thereto at 214 the downwardly extending arm 28 previously referred to. The arm 28 at its lower free end is adapted to be interposed between an upwardly extending arm 217 of the lever 26 and the pin 29 forming a part of the slide 30 and when so interposed it will be seen that the lower portion of said arm 28 constitutes a connecting member between the manually operated actuating member 26 and the tripper slide 30. Another arm 218 of the lever 26 is engaged by an extension 219 on the arm 39, against which it is normally held by a spring 220 except when the rod 25 and arm 39 are raised to lift the presser foot 38, at which time the movement of the lever 26 will be limited by the arm 218 engaging the end of a slot 221 through which said arm projects.

A spring 222 normally tends to hold the arm 28 in engagement with the arm 217, as illustrated in Fig. 7, at which time the end 208 of the rod 205 will be in the position illustrated in Figs. 2 and 5. A spring plate 223, pivoted at 224 upon the inside of the frame 20, has fast thereto a stud 225 which projects through an opening 226 in the frame 20, said stud having mounted thereon a spring 227 which bears at one end against the frame 20 and at the other end against an adjusting nut 228 upon said stud.

The spring plate 223, at its lower end, bears against one end of the tripper slide 30 and always tends to push said tripper slide toward the left, Fig. 7, and into a position to engage the locking dog 24, thereby stopping the machine. The pin 29 fast to the tripper slide 30, projects through an opening in the frame 20 and engages the lower end of the swinging arm 28. A stop pin 229 limits the movement of the arm 28 and the tripper slide 30 toward the left, Fig. 7, while contact of the arm with the frame at 230 limits the movement of said arm and slide toward the right.

The general operation of the mechanism hereinbefore described is as follows: Assuming the parts of the clutch controlling

mechanism to be in the relative positions illustrated in Fig. 7 and the operator wishes to throw the clutch into operation, he rocks the treadle in the proper direction to lower the rod 25 and thereby rocks the lever 26 and arm 28 whereupon the tripper slide 30 will be withdrawn from in front of the locking dog 24 allowing said locking dog to engage the driving pulley 22 and start the machine.

During the operation of the machine, the link 67 will be moved upwardly by the cam lever 69 and cam 70 and this will cause the lever 122 to rock in the reverse direction to that indicated by the arrow *a*, Fig. 2 and 80 thereby through the connecting rod 121, lever 119 and pawl 164, the ratchet 175 will be moved forward one tooth.

The cycle of operations is then repeated and with each successive rocking movement 85 of the lever 119, the pawl 164 will feed the ratchet 175 forward one tooth and the locking pawl 199 will hold said ratchet in its advanced position against the tension of the spring 178 while the pawl 164 is returning 90 to engage a new tooth.

As the ratchet 175 is thus rotated, step by step, it will eventually arrive at the position illustrated in Fig. 5 and the latch 193 will be moved from the position illustrated in 95 Fig. 2 to that illustrated in Fig. 5 by the pin 198, which being fastened to the ratchet 175 will be carried by said ratchet into engagement with said latch and thus said latch will be moved to the position illustrated in Fig. 5.

In the position illustrated in Fig. 5 it will be seen that the ratchet is held against rotation by the locking pawl 199. The pawl 164 will now be moved backwardly until the 105 end thereof engages the latch 193 which will operate to throw said pawl out of engagement with the ratchet; then upon the next forward movement of the pawl 164 said latch will be moved to the position illustrated in Fig. 6.

The pawl 164 will now engage the pawl 199 and throw it out of engagement with the ratchet 175 and said ratchet will then be carried back by the spring 178 from the 110 position illustrated in Fig. 5 to that illustrated in Fig. 6 and will be stopped by the pin 177 coming in contact with the side of the presser foot 38.

During the latter part of the last forward movement of the pawl 164 which carries the latch 193 from the position illustrated in Fig. 5 to that illustrated in Fig. 6, the arm 195 will engage the downwardly turned end 208 of the rod 205 and move said rod in the direction of the arrow *c*, Fig. 2, thereby rocking the shaft 211 and raising the arm 28. This upward movement of the arm 28 will disengage the lower end of said arm from the arm 217 of the lever 26 thereby re- 125 130

4
 leasing the spring actuated tripper slide 30 and allowing said tripper slide to be engaged by the locking dog 24, whereupon the driven member 23 of the clutch will be disengaged from the driving pulley member 22 and the machine will stop automatically without the operator removing his foot from the treadle. The operator may stop the machine if he so desires at the completion of each rotation of the shaft by removing his foot from the treadle, which will cause the rod 25 to rise and thereby allow the parts to assume the relative positions illustrated in Fig. 7.

15 The machine having been automatically stopped the operator now rocks the treadle and raises the presser foot 33 a sufficient distance to disengage the latch 193 from the pawl 164, whereupon the pawls 164 and 199 will return to the positions illustrated in Fig. 2 and the machine is now ready for a new sequence of operations.

It will thus be seen that by means of the mechanisms hereinbefore described that a 25 predetermined number of rotations of the main shaft of the machine or a predetermined number of sequence of operations of the mechanisms embodied in a machine may be obtained and the machine automatically 30 stopped at the completion of the predetermined number of rotations or sequences.

If desired, the mechanism hereinbefore described can be operated to stop the machine at the end of each rotation of the shaft and this may be done by operating the treadle to depress the rod 25 and thus operate the lever 26 and through the connecting member 28 and pin 29 the tripper slide 30 will be moved out of engagement with the locking dog 34 and the clutch will then operate the machine to rotate the shaft and actuate the mechanisms operated by said shaft. The operator releases the treadle before the completion of one rotation, whereupon the rod 40 45 will move upwardly and the lever 26 being thus released the tripper slide will be moved toward the left, Fig. 7, by the spring 223 until it is engaged by the dog 24 whereupon the driving member 22 of the clutch 50 will be disengaged by the driven member 23 and the machine will be stopped.

I claim:

1. A stop mechanism having, in combination, a rotary shaft, a clutch on said shaft, 55 a spring actuated tripper adapted to engage said clutch and unlock the driving member thereof from said shaft, means to move said tripper out of engagement with said clutch comprising a manually operable actuating member and a connecting member adapted to be interposed between said actuating member and said tripper and means actuated by said shaft to automatically move said connecting member out from between said actuating member and said tripper whereby said

tripper at the end of a predetermined plurality of rotations of said shaft may be released and allowed to engage said clutch to unlock the driving member from the driven member of said clutch and stop said machine. 70

2. A stop mechanism having, in combination, a rotary shaft, a clutch on said shaft, a spring actuated tripper adapted to engage said clutch and unlock the driving member 75 thereof from said shaft, means to move said tripper out of engagement with said clutch comprising a manually operated actuating member, a pivotally mounted arm, the free end of said arm adapted to be interposed between said actuating member and said tripper and means actuated by said rotary shaft to automatically move said arm out from between said actuating member and said tripper at the end of a predetermined 80 plurality of rotations of said shaft, whereby said tripper may be released and allowed to engage said clutch to unlock it from said shaft and stop said machine.

3. A stop mechanism having, in combination, a shaft, a clutch pulley rotatably mounted on said shaft and constituting a driving member, a driven member fast to said shaft, a locking dog pivoted to said driven member and adapted to engage said driving member, a tripper slide normally adapted to engage said locking dog to disengage said dog from said driving member, a manually operated lever, an arm interposed between said lever and said tripper slide adapted when moved by said lever to move said slide out of engagement with said locking dog, whereby said driving member and said driven member will be locked together to start said machine in operation, and means to disengage said arm from said lever at the end of a predetermined plurality of rotations of said shaft, whereby said tripper slide will automatically engage said locking dog and disconnect said driving member from said driven member and stop said machine. 100 105 110

4. A stop mechanism having, in combination, a rotary shaft, a clutch pulley rotatably mounted thereon and constituting a driving member, a driven member fast to said shaft, a locking dog pivoted to said driven member and adapted to engage said driving member and thereby lock said driving member and said driven member together, a tripper slide, a treadle mechanism, a member interposed between said tripper slide and said treadle mechanism adapted to engage said tripper slide to move said slide out of engagement with said locking dog and thereby allow said driving member and driven member to be locked together by said dog and mechanism adapted to automatically disengage said tripper slide from said treadle mechanism at the end of a pre- 115 120 125 130

determined plurality of rotations of said shaft, whereby said driving member and said driven member may be disengaged one from the other and said machine stopped.

- 5 5. A stop mechanism having, in combination, a shaft, a clutch comprising a pulley rotatably mounted upon said shaft and constituting a driving member, a driven member fast to said shaft, means for connecting 10 said driving member and said driven member together, means to disconnect said driving member and driven member and mechanism for automatically controlling said disconnecting means to cause stopping of said 15 machine after a predetermined number of rotations of said shaft, said mechanism including a vertical stud, a ratchet fast to said stud, a latch loosely mounted upon said stud, a lever pivoted upon said stud, a pawl

mounted upon said lever and adapted to engage said ratchet, means to rock said lever whereupon said ratchet may be advanced step by step, a pin fast to said ratchet adapted to engage said latch, whereupon said latch will be given a step by step movement, and means adapted to be operated by said latch to operate said disconnecting means, whereby said driving member and driven member of said clutch will be automatically disconnected.

In testimony whereof I have hereunto set my hand in presence of two subscribing witnesses.

ARTHUR R. HAVENER.

Witnesses:

CHARLES S. GOODING,
FRANKLIN E. LOW.
